Application October 20, 1948, Serial No. 55,457
In the Netherlands November 4, 1947

6 Claims. (Cl. 315—24)

1

This invention relates to a circuit arrangement for producing pulses of short duration and more particularly to a pulse generating circuit arrangement comprising a tube in which an electron beam is produced and in which the deflection of the beam is controlled by a locally generated oscillation.

The principal object of the invention is to provide a circuit arrangement of the above type in which pulses, including high frequency pulses, may be produced in a simple manner.

Further objects of the invention will appear from the following description.

According to the invention, in a tube of the above type, the electrons impinge on an output system which is arranged in such manner that all, or at least a major part, of the electrons emitted during each cycle of the local oscillations strike the output system substantially simultaneously.

In a preferred embodiment of the invention, the output system is shaped as a helical surface, the axis of the helix coinciding with the axis of a cone generated by the electron beam as it travels under the influence of the local oscillations, and the spacing between the ends of the output system in the direction of movement of the electrons being substantially equal to the path travelled by an electron during the cycle of the locally produced oscillation.

In order that the invention may be clearly understood and readily carried into effect it will now be described more fully with reference to the accompanying drawing in which

Fig. 1 illustrates one form of a circuit arrangement according to the invention, and

Fig. 2 illustrates another embodiment of a circuit arrangement according to the invention.

Fig. 1 shows a circuit arrangement according to the invention, comprising a discharge tube in which the cathode-system substantially consists of the cylindrical electron-emitting member 1 and a pierced disc 3 which has a positive potential with respect to the member 1 and which serves to form the emitted electrons into a beam. The tube further comprises a system of deflection electrodes 4, 5, 6, 7 which are arranged in pairs, the electrodes of a pair being parallel to each other and the pairs being perpendicular to each other, a screen 35 and an output system 31, 32. The electron-beam travels along the axis of the tube until it reaches the deflection system 4, 5, 6, 7 by which it is deflected. Voltages having the frequency of a local oscillator are applied as control-voltages between the terminals

2

18 connected to the electrodes 4 and 5. Voltages of the oscillator frequency are also applied between the terminals 19 connected to the electrodes 6 and 7, but these voltages are shifted in phase by 90° with respect to the voltages applied to the terminals 18. In this manner the beam is caused to define a circular trace, for example in the direction of the arrow, the frequency of rotation being equal to the local-oscillator frequency.

The output electrode 32 is shaped as a helix having a single turn. The axis of the helix coincides with the axis of the system. The helix may be imagined to result from moving a line element 15 along a spiral in such manner that this line element steadily remains at right angles to the axis of the spiral and remains directed to this axis, the ends of the turn being spaced apart from one another by a distance substantially corresponding to the path travelled by an electron during one cycle of the local oscillation.

There may further be provided a grid 35 which has a positive potential and which serves to obtain a suitable configuration of the field on the right thereof. This field is preferably an equi-potential field. The voltages set up at the electrodes are so chosen that the conical surface generated by the electron beam intersects the anode 31. It is assumed that the beam travels in the direction of the arrow indicated in the drawing. The pulses obtained are derived from a circuit between the points 33 and 34, which are connected respectively to the output electrode 31 and a grid-shaped electrode 32 which is located in front of the output electrode 31 and shaped similarly thereto. Assuming that, at a given instant, the beam just strikes the left-hand end of the output electrode 31, then none of the electrons will provisionally be able to reach the anode 31 during the further movement. If the spacing of the two ends in the direction of travel of the electrons exactly corresponds to the path travelled by an electron during one cycle of the local oscillation, the electrons present at the left-hand end at the starting instant will just reach the right-hand end when the beam also arrives at this point. An electron present at the plane of the beginning of the helix one half cycle after the starting instant will, in its turn, likewise reach the output electrode one half cycle later, in other words the output electrode is simultaneously struck by all electrons of the beam emitted during one oscillator-cycle. If the helical output electrode is constructed regularly, the impact takes place in a very short time, so that

in this manner extremely short pulses can be produced with the frequency of the local oscillator.

The arrangement described comprising a helical anode cannot be used for a flat, tape-shaped electron-beam since the latter is poorly adapted to be deflected by a control voltage in a direction in the plane of the beam. Yet the use of such a beam is often desirable, since it exhibits the advantage of being able to convey a greater current with the same thickness and the same voltage, because less trouble is experienced from space charges.

Fig. 2 represents a device according to the invention in which use may be made of a tape-shaped beam in combination with linear deflection by the oscillator voltage at right angles to the plane of the beam.

The arrangement shown in Fig. 2 also comprises a cathode-system 1 which, in this case, emits a tape-shaped electron-beam. The beam traverses the space between the deflection plates 36 and 37 of which the plane extends parallel to the plane of the beam. The oscillator voltage is applied to these deflection plates and consequently confers on the beam a deflection at right angles to its plane in accordance with the instantaneous values of the oscillator voltage. The beam travelling at right angles to its plane in accordance with the oscillator-voltage may again be caused to traverse a positively charged grid 35. In this case the output electrode 38 is of a special shape and is, more particularly, curved in such manner that the lines of intersection with planes at right angles to the electron beam substantially exhibit the form of a half cosine curve, the sections with planes parallel to the plane of the beam being substantially straight. Furthermore, the curvature of the anode 38 is such that the difference in transit time of the electrons passing to the lower end and of the electrons passing to the upper end amounts approximately to one half cycle of the local oscillation. In front of the anode 38 and slightly spaced apart therefrom is arranged a grid 39 having the same shape. The anode 38 and the grid 39 are connected to conductors 40 and 41 located beyond the surrounding tube, from which conductors the pulse-shaped voltages can be taken.

Assuming furthermore that the oscillator voltage also varies practically sinusoidally with the time and the size of the anode and the value of the voltages are such that the beam changes its direction to the lower end of the anode into a direction to the upper end of the anode during one half cycle of the local oscillation, all electrons emitted during one half cycle of the oscillator-oscillation will strike the anode simultaneously. In contradistinction to the device shown in Fig. 1, the electrons emitted during the other half cycle of the local oscillation are not utilised.

The pulses produced by the aforesaid circuit-arrangement may be used for various purposes, for example for mixing with ultra-high frequency oscillations and frequency-multiplication.

What we claim is:

1. A pulse generator circuit arrangement, comprising a source of oscillations having a given frequency, an electron discharge tube comprising means to form an electron beam and to direct said beam along a given path, deflecting means arranged about said path, means to apply said oscillations to said deflecting means to cause said beam to define a circular trace and an anode elec-

trode comprising a helically shaped surface having a single convolution about a central axis coinciding with said path, said electrons having a given component of velocity along said path, said convolution having a given pitch substantially equal to the distance travelled by the electrons of said beam during a cycle of said oscillations, and means to derive from said anode the energy imparted thereto by said electron beam.

2. A pulse generator circuit arrangement, comprising a source of oscillations having a given frequency, an electron discharge tube comprising means to form an electron beam and to direct said beam along a given path, a plurality of deflecting electrodes arranged about said path, means to apply said oscillations to said deflecting electrodes to cause said beam to define a circular trace and an anode electrode comprising a helically shaped surface having a single convolution about a central axis coinciding with said path, said electrons having a given component of velocity along said path, said convolution having a given pitch substantially equal to the distance travelled by the electrons of said beam during a cycle of said oscillations, and means to derive from said anode the energy imparted thereto by said electron beam.

3. A pulse generator circuit arrangement, comprising a source of local oscillations having a given frequency, phase shifting means coupled to said source to produce phase shifted oscillations, an electron discharge tube comprising means to form an electron beam and to direct said beam along a given path, a pair of horizontal deflecting electrodes arranged about said path, a pair of vertical deflecting electrodes arranged about said path, means to apply said local oscillations to one of said pairs of deflecting electrodes and said phase shifted oscillations to the other pair of deflecting electrodes to cause said beam to define a circular trace and an anode electrode comprising a helically shaped surface having a single convolution about a central axis coinciding with said path, said electrons having a given component of velocity along said path, said convolution having a given pitch substantially equal to the distance travelled by the electrons of said beam during a cycle of said local oscillations, and means to derive from said anode the energy imparted thereto by said electron beam.

4. A pulse generator circuit arrangement, comprising a source of oscillations having a given frequency, an electron discharge tube comprising means to form an electron beam and to direct said beam along a given path, a plurality of deflecting electrodes arranged about said path, means to apply said oscillations to said deflecting electrodes to cause said beam to define a circular trace, an anode electrode comprising a helically shaped surface having a single convolution about a central axis coinciding with said path and a grid electrode having a shape similar to the shape of said anode interposed between said anode and said deflecting electrodes, said electrons having a given component of velocity along said path, said convolution having a given pitch substantially equal to the distance travelled by the electrons of said beam during a cycle of said oscillations, and means to derive from said anode and said grid the energy imparted thereto by said electron beam.

5. An electron discharge tube for producing electrical pulses having a given periodicity, comprising means to form an electron beam and to direct said beam along a given path with a given

velocity, deflecting means arranged about said path, and adapted to cause said beam to define a circular trace, and an anode electrode comprising a helically shaped surface having a single convolution about a central axis coinciding with said path, said convolution having a pitch substantially equal to the distance travelled by the electrons of said beam during a period of said pulses.

6. An electron discharge tube for producing electrical pulses having a given periodicity, comprising means to form an electron beam and to direct said beam along a given path with a given velocity, a plurality of deflecting electrodes arranged about said path and adapted to cause said beam to define a circular trace, an anode electrode comprising a helically shaped surface having a single convolution about a central axis coinciding with said path, said convolution hav-

ing a pitch substantially equal to the distance travelled by the electrons of said beam during a period of said pulses, and a grid electrode having a shape similar to the shape of said anode interposed between said anode and said deflecting electrodes.
